UNITED STATES PATENT OFFICE.

PHILIP A. MYERS, OF ASHLAND, OHIO.

HAY-CARRIER.

SPECIFICATION forming part of Letters Patent No. 291,852, dated January 8, 1884.

Application filed September 11, 1883. (No model.)

To all whom it may concern:

Be it known that I, PHILIP A. MYERS, of 5
Ashland, in the county of Ashland and State
of Ohio, have invented a new and useful Im-
provement in Hay-Carriers; and I do hereby
declare that the following is a full, clear, and
exact description of the same.

My invention is an improvement in hay-car-
riers of that class adapted to run upon an ele-
10 vated track to be held by a suitable catch
while raising the load, to automatically release
the latch when the load is raised, and to hold
the load suspended during its horizontal move-
ment.

15 My object may be stated in general terms to
be the improved construction of the parts,
whereby they are rendered more simple, in-
expensive, and durable, and whereby, also,
every operation is made more certain and ef-
fectual. I have aimed to avoid the use of
20 springs and to free the latch from any defect-
ive operation by reason of the swinging of the
carrier from side to side. The carrier is adapt-
ed specially to run upon a track composed of
25 a rod or wire rope, but may be used also with
a bar or equivalent form of track.

In the accompanying drawings, Figure 1
represents a side elevation of my improved
carrier with a part of the track, the carrier
30 being latched in position to receive a load and
the hook-pulley partly lowered. Fig. 2 repre-
sents the carrier partly in longitudinal ver-
tical section in the same position, but with the
forked lock raised and the latch partly re-
35 leased. Fig. 3 is a section of line $x-x$ of Fig.
2. Fig. 4 is an end view of the track, show-
ing the loop or detent which holds the latch
and operates the dog. Figs. 5 and 6 show
modifications hereinafter explained.

40 The body of the carrier is composed of a
pair of bent flat bars, $a a$, and they are con-
nected to each other with distance-pieces by
means of the bolts on which the sheaves and
other parts are pivoted, and are separated far
45 enough to allow space for the latch and dog
hereinafter described. The frame is suspended
from the track by means of pairs of straps 1
and 2. Of these straps pair 1, which is on the
rear of the carrier, is riveted near the bend
50 and carries a sheave, 3, on its upper end. The

other pair is riveted on each side to the for-
ward end of the carrier with a sheave, 4, above,
to run upon the track, and below a sheave, 5,
for the hoisting-rope. The bars a may be bent
either in the shape shown in Fig. 1 or in that 55
shown in Fig. 5, the difference being simply
that in the latter the bent end is projected far-
ther forward. Within these bent ends is piv-
oted a bell-crank lever, A. It has a hollow or
grooved shank, b, adapted to receive the rope, 60
and an arm, c, adapted to operate the latch
and to be held by the dog when the load is
hoisted. The latch and dog are shown in the
side elevation, partly in dotted lines. The
latch (marked B) is a flat bar pivoted upon the 65
bolt 6 and extending rearward between the
bars $a a$. A hook on its rear end engages with
the loop or detent D, fixed to the end of the
track where the load is to be raised. The latch
is formed with a bend, 7, (shown more clearly 70
in Figs. 1 and 6,) which lies in the path of the
broad end 8 on the end of arm c of the bell-
crank lever, so that as the lever is swung up
by the elevation of the load the arm c, with
its broad end, comes into the position shown 75
in Fig. 2, and raises the latch, thus releasing
the carrier and permitting it to move forward
with its load. Also, between the two bars $a a$
and on the same pivot with the latch is pivoted a
dog, E. It is made of a flat bar of metal like the 80
latch, and has its free end bent, as shown more
clearly in Figs. 2 and 6. As it is also in the
path of the broad end of the arm c, it is also
raised by the movement of that arm when the
weight is elevated. The lower edge of the dog 85
is notched to form a shoulder, 9, and, being
free to fall, drops when the end of the arm c
has passed the notch and dogs the bell-crank
lever, thus supporting the load in an elevated
position, ready for movement upon the track. 90

It will be observed that the parts are in
such position that the arm c first passes be-
hind the shoulder of the dog shown, so that
it is in position to be retained securely in
place, and afterward strikes against the in- 95
cline 7 and lifts the latch, so that the load is
locked securely in place before the carrier can
start, making action of the parts absolutely
certain. Further, the dog, after the carrier
has left the detent or loop, cannot be inter- 100

ferred with, and holds the bell-crank lever securely in place, however much the carrier may sway from side to side.

It will be observed that the detent D is semi-circular in form, so that it receives the hook even if the carrier be swinging laterally as it approaches on its return for a load. Upon the return of the carrier to the loading position, the bell-crank lever remains locked, and in order that it may be automatically released the dog is provided with an upturned end, 10, which rides up on the detent and lifts the shoulder 9 away from the end of the arm e, thus allowing the hook to drop. The detent 15 D may be formed, as shown in Fig. 4, conveniently to clamp the track at any desired point. As will appear more clearly in Fig. 2, the lifting incline 10 of the dog is a little nearer to the carrier than the shoulder of the 20 latch. This permits the carrier to recede sufficiently from the detent before the latch takes hold to allow the dog to drop and be ready to operate on the bell-crank lever when the load is raised.

25 In Fig. 5 I have shown the bent ends of the bars a a, which form the body of the carrier, as extending far enough to the front to receive the sheave of the fork-block, so as to allow it to rest thereon during the movement 30 of the carrier. The only difference between this form and that shown in Figs. 1 and 2 is that in the latter figures the load rests upon the shank or arm of the bell-crank lever. In the form shown in Fig. 5, the weight rests upon 35 the carrier and brings no strain upon the bell-crank lever of the dog. Manifestly, the pulley 5 should be higher than the pivot of the bell-crank lever. In order to separate the latch and dog, I have provided a thin flat strap, 40 F, Figs. 5 and 6, which is inserted between the latch and dog and bolted below to the frame and above to the rear pair of straps. In order to cause the levers to act with promptness and certainty, I may also add a spring, g, 45 which is fixed to a stud on the bar F, or to any other convenient point, and extends forward to bear upon the upper edges of the latch and dog.

50 It will be observed that the general construction of the carrier is simple and of few parts, and in this respect is new. The construction and dog I regard also as an important part of my invention. Incidentally to the construction of the carrier is the important feature shown in Fig. 5, whereby the load is supported on the carrier itself, and requires only the locking of the lifting apparatus to keep it 55 in place.

I am aware that hay-carriers having frames adapted to run on a ropeway with hoisting-rope and bell-crank lever arrangement and dog are not new, and I do not broadly claim such a carrier.

I claim as my invention—

1. A hay-carrier consisting of two bent side 60 bars properly connected with hangers and supporting-sheaves, a bell-crank lever pivoted on the bent ends of the bars and connected to the hoisting-rope passing over a pulley on the carrier, a latch adapted to catch over a detent on 65 the way, and a dog to hold the bell-crank lever, the latch and dog being constructed to operate in connection with the detent, substantially as described.

2. The combination, in a hay-carrier, of a 70 latch and dog pivoted within the carrier, a bell-crank lever connected to the hoisting-rope and having an arm adapted to operate a latch and dog and be held by the dog, and a pulley for the hoisting-rope adapted to throw the lever-arm against the dog and latch, all substantially as described.

3. The combination, in a hay-carrier, of a bell-crank lever connected to the hoisting-rope, which is arranged to run over an elevated pulley, 5, an arm of the bell-crank lever, and a dog, E, fitted to be lifted by the arm and by the detent on the way, all substantially as described.

4. The combination, in a hay-carrier, of hoisting devices and a dog, E, adapted to be lifted by the hoisting devices, and a detent adapted to raise the dog, all substantially as described.

5. In a hay-carrier, the latch and dog pivoted 95 between the bars of the carrier, combined with a detent, D, and adapted to operate in connection with the detent, substantially as described.

6. The combination, with the described hay-carrier, of the latch B and dog E, both having inclines, whereby it is lifted by the hoisting devices and by the detent, all substantially as described.

7. The combination of the latch and dog with the hay-carrier supported by sheaves on a track, and the detent D, having semicircular 105 bar, all substantially as described.

8. In combination with the latch and dog of the described carrier, the separating-strap F, substantially as described.

In testimony whereof I have signed my name 110 to this specification in the presence of two subscribing witnesses.

PHILIP A. MYERS.
